(57) **CLAIM**

We claim, the ornamental design for a medical securing device, as shown and described.

DESCRIPTION

FIG. 1 is a top perspective view of a medical securing device, showing my new design;

FIG. 2 is another top perspective view thereof;

FIG. 3 is a bottom perspective view thereof;

FIG. 4 is a side elevation view thereof, the opposite side being a mirror image of thereof;

FIG. 5 is a front elevation view thereof; and,

FIG. 6 is a top plan view thereof.
